UNITED STATES PATENT OFFICE.

THOMAS J. FLAGG, OF NEW YORK, N. Y., ASSIGNOR TO FISK, CLARK & FLAGG, OF SAME PLACE.

DESIGN FOR A NECK-SCARF.

SPECIFICATION forming part of Design No. 11,783, dated May 18, 1880.

Application filed January 22, 1880. Term of patent 7 years.

To all whom it may concern:

Be it known that I, THOMAS J. FLAGG, a citizen of the United States, residing at New York, in the county and State of New York, have invented and produced a new and original Design for Made-Up Scarfs, of which the following is a specification, reference being had to the accompanying drawing, forming part thereof.

10 My design relates to a double-headed or reversible scarf formed with crossed aprons, whose opposite ends are finished and connected by an intermediate piece, so that either end of the scarf may be exposed and worn at

15 its head.
The leading feature of my design consists in the superposition of two scarf-aprons, each of which is bounded lengthwise by outwardly-curved lines, presenting, respectively, arcs of 20 long radii, and at one end by an inwardly-curved line the chord of whose arc is at right angles to the chords of the arcs of the lateral curves, and at the other by a straight line forming unequal angles with the lateral chords,

25 the corresponding ends of the aprons being placed in the same direction and joined by inwardly-curved lines extending from the adjacent angles or curves of said ends, the whole forming an ornamental configuration for a 30 double scarf, the two ends of which are each finished and complete in itself.

In the accompanying drawing, A A are the aprons of the scarf; b b, their lateral edges, bounded by curved lines, forming arcs of extended radii; c c, their inwardly-curved ends, 35 the chord of whose arc in each extends at right angles to the chords of the curved sides b b of the apron; d d, their opposite straight ends, bounded by a straight line, which forms unequal angles with the chords of the curved 40 sides b b; e e, inwardly-curved lines, connecting the adjacent angles of the ends of the aprons when crossed.

D is the neck-band of the scarf, forming, however, no part of the design. 45

I claim as my invention—

The design for a double-end scarf, herein shown and described, consisting of and produced by the superposition of the crossed aprons A A, each of which is bounded by the 50 lateral curved lines b b, the curved line c at one end, and straight line d at the other, the adjacent angles of the aprons at each end being connected by the curved lines e e, as set forth.

THOS. J. FLAGG.
